UNITED STATES PATENT OFFICE.

WILLIAM L. KELLERMAN, OF OSKALOOSA, IOWA, ASSIGNOR OF ONE HALF TO SCOTT H. HULL, OF OSKALOOSA, IOWA.

HARNESS-SADDLE.

No. 808,160.

Specification of Letters Patent.

Patented Dec. 26, 1905.

Application filed March 18, 1905. Serial No. 250,718.

To all whom it may concern:

Be it known that I, WILLIAM L. KELLERMAN, a citizen of the United States of America, and a resident of Oskaloosa, Mahaska county, 5 Iowa, have invented a new and useful Harness-Saddle, of which the following is a specification.

The object of this invention is to provide improved construction for harness-saddles.

10 A further object of this invention is to provide improved means for connecting a harness-saddle to a pad.

15 A further object of this invention is to provide improved means for connecting a pad-skirt to a harness saddle and pad.

A further object of this invention is to simplify the work of trimming a harness saddle and pad.

20 My invention consists in the construction, arrangement, and combination of elements hereinafter set forth, pointed out in my claims, and illustrated by the accompanying drawings, in which—

25 Figure 1 is an elevation, partly in section, illustrating my device. Fig. 2 is a cross-section on the indicated line 2 2 of Fig. 1. Fig. 3 is a perspective of a base-plate employed in the device. Fig. 4 is a perspective of a hook-plate employed in the device.

30 In the construction of the device as shown the numeral 10 designates a pad of double form, having a top leather 11 extending from end to end thereof. The pad may be constructed in any desired form so long as it retains the top leather 11 or its equivalent as an 35 element. A base-plate 12 is provided for and is mounted beneath each end portion of the top leather 11. Each base-plate is fixed to the top leather 11 by a rivet 13. Each base-

40 plate 12 is formed with an arch or offset portion 14 intermediate of its ends, which arches or offset portions extend upwardly through apertures in the top leather 11. A stud 15 is formed on each base-plate adjacent the arch 45 or offset portion 14 and extends upwardly through the top leather 11. A bolt-hole 16 is formed in the top of each arch or offset portion 14 and a slot 17 is formed in and transversely of the inner end portion of each base-plate 12. A bur 18, formed with laterally-extending wings 19, is mounted loosely in the arch or offset portion 14 of each base-plate and the ends of the wings rest on the top leather, the threaded aperture of the bur reg-

istering with the bolt-hole 16. Apertures or 55 slots 20 are formed in the top leather 11, registering with the slots 17 of the base-plates. A pad-skirt 21 is provided at each end of the pad 10. The pad-skirts are provided with holes 22 to receive the studs 15 and rest on 60 the upper surface of the top leather, the upper ends of the pad-skirts abutting the arches or offset portions 14. A saddle-piece 23 is mounted above the central portion of the top leather 11 and is formed with a slot 24 in each 65 end, registering with the slots 17 and 20. Hook-plates 25 are provided and are adapted to overlie the upper end portions of the pad-skirts 21 and the arches or offset portions 14. The hook-plates 25 are formed with 70 hooks 26 and forwardly-extending lips 27 on the extremities of said hooks, the hooks extending through the slots 24, 20, and 17 and the lips extending toward each other beneath the top leather and retaining the hooks in the 75 slots. The hook-plates 25 are formed with end flanges 28, adapted to engage the top leather 11 and make a finish adjacent the hooks 26 and side flanges 29, extending downward across the side margins of the pad-skirts 80 and making a finish at the sides of said plates. Terrets 30 are provided, and the bolts 31 thereof extend through holes in the hook plates and arches and seat in the burs 18. The terrets and their bolts, in connection with the 85 burs 18, firmly and securely connect the base-plates, top leather, pad-skirts, and hook-plates, and the hooks firmly yet flexibly connect the saddle-piece 23 to the base-plates and top leather. The top leather is flexible and 90 the hooks loosely embrace the end bars of the saddle-piece, thus providing hinges or flexing-points at each end of the saddle-piece.

It will be observed that in the construction above defined I avoid using several screws or 95 equivalent fastening means, and through the medium of the studs 15, hooks 26, and terret-bolts I effect simpler and safe connections between the parts. By offsetting the arches 14 through the top leather and mounting the 100 burs 18 between said arches and top leather I avoid extending the terret-bolts into the pad and consequent difficulty of properly attaching the bolts to burs in the pad.

I claim as my invention—

105 1. A harness-saddle, comprising a pad, base-plates mounted in said pad and formed with arches extending through the top of said pad,

burs mounted between said arches and the top of the pad, studs on the base-plates extending through the top of the pad, pad-skirts adapted to be engaged by said studs, hook-plates adapted to overlie the arches and pad-skirts, hooks on said hook-plates engaging the top of the pad and the base-plates, a saddle-piece flexibly connected to said hooks, and terrets engaging said burs and adapted to bind the hook-plates to the base-plates.

2. In a harness-saddle, a pad, a base-plate in said pad, a portion of said base-plate arched through the top of said pad and apertured, a bur loosely confined in the arched portion of the base-plate, and a terret extending through said arched portion of the base-plate and seated in said bur.

3. A harness-saddle, comprising a pad, base-plates in said pad, apertured arches intermediate of the ends of said base-plates and extending through the top of the pad, pad-skirts

on said base-plates, a saddle-piece connecting said base-plates, hook-plates hinging the base-plates and saddle-piece together, and terrets connecting the hook-plates to the arches of the base-plates.

4. A harness-saddle, comprising base-plates, each base-plate formed with an arch intermediate of its ends and centrally apertured, a bur within the arch with its aperture registering with the aperture in the arch, a saddle-piece connecting the base-plates, hook-plates engaging the saddle-piece and base-plates flexibly, and terrets mounted through said hook-plates and arches and seated in said burs.

Signed by me at Oskaloosa, Iowa, this 14th day of March, 1905.

WILLIAM L. KELLERMAN.
